CLAIM

The ornamental design for a poultry nourishment device, as shown and described.

DESCRIPTION

FIG. 1 is an exploded upper perspective view of the poultry nourishment device in which a base is shown disengaged from the jar component of the device;

FIG. 2 is an upper perspective view of the poultry nourishment device in which a base is shown engaged with the jar component of the device;

FIG. 3 is an exploded rear upper perspective view of the poultry nourishment device in which a base is shown disengaged from the jar component of the device;

(Continued)

FIG. 4 is an exploded lower perspective view of the poultry nourishment device in which a base is shown disengaged from the jar component of the device;

FIG. 5 is an offset top view of the poultry nourishment device in which the exemplary jar component and base are shown disassembled from each other;

FIG. 6 is a bottom view thereof;

FIG. 7 is an exploded side view of the poultry nourishment device; and,

FIG. 8 is a side view of the poultry nourishment device, shown in a fully assembled condition.

1 Claim, 8 Drawing Sheets
